UNITED STATES PATENT OFFICE.

NATHAN F. FRETTER, OF CLEVELAND, OHIO.

MACHINE FOR CUTTING BAR-STOCK OR THE LIKE.

1,366,783.

Specification of Letters Patent. Patented Jan. 25, 1921.

Application filed March 29, 1919. Serial No. 286,182.

To all whom it may concern:

Be it known that I, NATHAN F. FRETTER, a citizen of the United States, residing at Cleveland, in the county of Cuyahoga and State of Ohio, have invented a certain new and useful Improvement in Machines for Cutting Bar-Stock or the like, of which the following is a full, clear, and exact description, reference being had to the accompanying drawings.

This invention relates to machines for cutting or sawing bar stock, I-beams, and the like into pieces of any desired length. More particularly, the invention relates to machines of the aforesaid nature involving a number of saws or cutters.

The main objects of my invention are to provide a substantial and durable machine of the above character that is highly productive; is convenient and economical of operation and maintenance, and that is comparatively simple of construction.

Other objects are to provide a machine of the above nature that is adjustable to the cutting of stock of different diameters and cross-sectional shapes; that is adjustable to produce pieces of different lengths; and that can be readily supplied with a greater or less number of saws or cutters and associated work supports, whereby the capacity of the machine may be altered at will.

Further objects of the invention are to provide a multiple sawing machine or cutter involving individual supports for the separate, cut pieces and a holding means associated with each support; to provide a common clamping member through which the several holding means may be operated in unison and with uniform pressure; and to provide mechanism whereby the several holding means may be simultaneously relaxed and retracted to permit the removal of cut pieces, and the introduction of a fresh bar of stock.

The invention has for further objects, other improvements, and consists in certain novel constructions and combinations as will be hereinafter described and claimed.

In the drawings, Figure 1 is a plan view of the machine, certain parts being shown in section; Fig. 2 is a side elevation of the machine; Fig. 2^a is a sectional detail on line 2^a of Fig. 2; Fig. 3 is a longitudinal vertical section through the machine substantially on the line 3—3 of Fig. 1 and looking in the

direction of the arrows; Fig. 4 is a section on line 4—4 of Fig. 5; Fig. 5 is a sectional view on line 5—5 of Fig. 1, showing the change-speed-gearing and drive; Fig. 6 is an enlarged perspective view of a holding means or clamp associated with one of the individual work holders or cut-piece supports; Fig. 7 is a similar view of one of said work holders or supports; and Fig. 8 is a detail of the shaft and associated parts used to move the common clamping member of the several holding means or clamps.

The frame of the machine consists of a base 1 incorporating a cross web 2 and a drain basin 3, the latter being situated toward the front of the machine. The frame involves a support 4 that serves as an abutment for work holders 5, and the support has, in its upper horizontal surface, a longitudinal groove 6.

Guides 7 extend along the upper edge portions of the sides of base 1 from the rear of the machine to a point beyond its middle, and at the extreme rear end of each guide is a lug 8 through which an adjusting screw 9 is threaded to limit the rearward travel of a cutter carriage 10, which is slidably mounted on the guides 7, and is held in place by gibs 11, secured to the carriage by screws 12.

The cutter carriage (which for the purpose of claims, may in some instances be referred to as the sustaining element), is shown as rising somewhat above the plane of support 4, and as being hollow in its center, and it has a longitudinal groove 14 in its upper horizontal surface, on which surface are slidably supported the cutter guides 15, and cutter arbor bearing brackets 16, the guides and brackets having tongues for engagement within the groove 14. To the rear of and secured to the cutter carriage 10, are racks 18, one lying along the upper side of each guide 7, and these racks are limited in their rearward movements by the previously mentioned screws 9. Secured to carriage 10 is a cable 19 that is guided over a sheave 20, supported by a bracket 21 that extends upwardly and rearwardly from web 2. A weight 22 is attached to the cable for returning the carriage to starting position after a cutting expedition, as I shall presently explain.

An arm 23 extends forwardly from the left hand side of carriage 10, the arm being

shown as formed integral with the carriage; and adjacent its forward end, the arm forms a bearing for the left hand end of a cutter arbor 24. At its opposite end, and at its middle, the arbor is also supported in the previously mentioned movable brackets 16 which overhang the front of the carriage, and are formed with depending portions 25, which bear against the vertically disposed front wall of the cutter carriage. The brackets are guided properly with respect to the carriage, when adjusted transversely thereof, and are prevented from turning to either side, by the engagement of their tongues 15 within the groove 14 of the carriage, as previously mentioned. The brackets 16 also have tongues 27 on their top sides which fit a longitudinal groove 28 in a main clamping member 29, to maintain them in proper position with respect to the member, as I shall presently explain.

The cutter arbor 24 has a keyway 30 extending its entire length, and sets of collars 31 are slideable along the arbor but are held 25 against turning with respect thereto by the engagement of their integral keys (see Fig. 3) within keyway 30. A circular saw or cutter 32 is held between the collars of each set, and the saw and collars are effectually 30 restrained against relative angular movement by dowel pins 33 which are carried by one collar and pass through apertures in the saw and enter holes in the other. The collars may be held in any adjusted position 35 along the arbor, and those of each set in proper relation to each other, by set screws 34 that are threaded through the collars and bear against the arbor.

The saw guide and guard 15, which partially surrounds each saw 32, has radially disposed sets of rollers 35 that are angularly spaced from each other a suitable distance apart and are adjustably brought to bear upon the opposite sides of the saw through 40 the instrumentality of clamping screws 36 which go through the opposed wings of the guard. The shank 37 of each guard is guided similarly to the arbor bearing brackets 16, the shank having a tongue 38 on its 45 lower side and a tongue 39 on its upper side for engagement within the respective grooves of the cutter carriage 10 and previously mentioned clamping member 29. The guard has a depending portion 40 which 50 bears against the vertically disposed front wall of the cutter carriage to withstand rearward thrust of the guard.

The main clamping member 29 extends 55 transversely the width of the cutter carriage. Mounted at each end of said member is a vertically disposed screw 41 which has its upper end threaded through a bracket, the one situated at the left hand side of the machine (viewing it from the front) being designated 60 42 and the one at the right hand

side, 43. These brackets are secured to the cutter carriage by bolts 44 and 45 respectively. Each screw 41 is guided at its lower end within a tubular boss 46 of the clamping member 29, and is provided therebeyond 70 with a collar that occupies a counterbore in the underneath side of the clamping member.

Between each boss 46 and a shoulder 47 on the corresponding screw 41 is a worm wheel 48 that is fixed to the screw and arranged to be driven by a worm that is fastened to the adjacent end of a shaft 49, journaled in bearings 50 extending from the clamping member 29. Secured to the right hand end of said shaft is a handle 51 through 75 which the shaft may be manually rotated to turn the aforesaid worms and consequently the worm wheels 48, thereby to operate the screws 41 and raise or lower clamping member 29 as desired. The bracket 43 is so shaped as to permit the arbor brackets 16 and saw guards 15 to be readily taken off and put on from the right hand side of the machine.

Each work holder 5 has a V-shaped groove 50 or notch 52 arranged to receive the work which may be in the nature of round stock as indicated, or it may consist of a multiple of bars of relatively small diameter grouped together in a manner well known to those familiar with the art. It is obvious that the work holders may be formed with any desired shape of work receiving notches or grooves according to the character of the stock to be cut. For the purpose of claims 100 the work holders generally may be referred to as "means for supporting an article to be cut", or simply "supporting means." The work holders rest on a horizontal shelf 53 that extends rearwardly from the support 4 and terminates at its rear edge in a downwardly inclined lip 54, provided for a purpose presently to be explained. Each work holder has its lower front corner cut away, as indicated at 55, where it meets the 105 angle between the shelf 53 and support 4 to allow for any irregularities in the machining of the base and to insure an even bearing of the work holder on its support. A projection 56, somewhat wider than the work 110 holder, extends forwardly from the upper end of each and overlies the upper surface of support 4. The projection has a depending tongue that is guided in a longitudinal groove of the support.

In the projection 56 of each work holder is a groove 57 wherein is guided a holding means or clamp 58 having a downwardly extending lip 59 at its front end for engagement with the corresponding end of 125 the projection to limit the rearward movement of the holding means or clamp. The rear end of the clamp is inclined upwardly as indicated at 60 and is then directed horizontally (see Fig. 6), and a screw 61 is 130

threaded through the horizontal portion. When the clamps 58 are in effective position their screws 61 bear upon the work to hold the same in place during the cutting or sawing operation; and once the screws are adjusted for work of a given size, they need not be altered so long as the machine continues to operate on work of that size. The reason for this will become apparent 10 from the description immediately following.

A main clamping member 62 coöperates with the several holding means or clamps 58 in a manner substantially identical with 15 that in which the former clamping member 29 coöperates with the saw guards 15 and brackets 16, hereinbefore described. Each clamp 58 has a tongue 63 that occupies a longitudinal groove in the underneath face of the main clamping member 62. Slides 64 and 65 are guided, respectively, in grooves formed in the tops of brackets 66 and 67, and these brackets are situated, respectively, at the right and left 25 hand front corners of the machine and are fastened to the base thereof by screws 68. Each slide has a tapped hole in which a vertically disposed screw 69 operates; and said screw is connected with the main 30 clamping member 62 precisely as each of the previously mentioned screws 41 is connected to the clamping member 29.

Mounted loosely on a shaft 70 slidably supported in brackets 70^a that extend upwardly and forwardly from the clamping member 62, are a set of spur gears 71 and 72, which are adapted to mesh with racks 73 and 74 secured to the respective brackets 66 and 67. Similarly mounted on shaft 70 40 are worms 75 and 76. The gears and worms are each situated between and restrained against endwise movement by adjacent ones of the aforesaid brackets 70^a. Each worm and gear has a counterbore 79 (see Fig. 8) 45 from which extend diametrically opposed notches 80 arranged to receive the ends of driving pins 81 that are carried by the shaft, when the shaft is slid in an appropriate direction.

50 It will be observed that the worms mesh with worm wheels 69^a on screws 69. By means of a handle 70^b, that is attached to the right hand end of shaft 70, the operator may shift the shaft in a direction to clutch the worms to the shaft, then turn the shaft in a direction to rotate screws 69 and elevate the clamping member 62 to relax the clamps 58 and bring spur gears 71 and 72 into mesh with their respective racks. Now 55 by shifting the shaft in the opposite direction, he may unclutch the worms and clutch the gears to the shaft, after which, by rotating the shaft in the proper direction he may feed the clamping member 62, with 60 clamps 58, forwardly to permit ready access

to the work in the holders. Upon supplying the holders with fresh material, the foregoing operation may be reversed to clamp the work within the holders. By reason of the fact that the relaxing of the 70 clamps and the shifting of them from holding position are sequential steps of a continuous operation, the operator is precluded from shifting the clamps laterally while forcefully engaged with the work and is 75 thereby prevented from injuring the machine.

A shaft 82 is supported transversely of the machine and to the rear of the cutter carriage 10 in brackets 83 and 84 that are 80 located respectively on the right and on the left hand sides of the machine base and are secured thereto by screws 86. Gears 85 are fixed to shaft 82 and mesh with the racks 18 of the cutter carriage. Projecting from the 85 outer face of the left hand gear 85 are two radially disposed lugs 87 that are adapted to be engaged and driven by a clutch member 88. This clutch member slides in the bearing 84 and has splined on its outer end 90 a bevel gear 89 which has its hub resting against the outer face of said bearing 84.

The bevel gear 89 meshes with a bevel gear 90, secured to a shaft 91. The latter shaft extends at right angles to shaft 82 95 and is journaled in a bearing 92 of bracket 84 and in two vertical arms 93 (Figs. 4 and 5) of a change-speed-gear bracket 94. The bracket 94 is fastened to the side wall of the base at the front of the machine by 100 screws 95 and is formed to constitute an oil basin for the change-speed-gears which I shall presently describe.

An arm 96 projects rearwardly from bearing 84 and has pivoted to its end, a clutch shifting member 97. Connection between the member and clutch is accomplished in the usual manner by providing the clutch with a groove and the shifting member with opposed pins projecting into the groove, one 105 of the pins being shown at 100. The outer ends of the links of a toggle joint 101 are connected respectively to the free end of the clutch shifting member 97 and to a lug 102 110 on the front side of bearing 84, while the knee of the toggle has connection with a bar 104 that extends along side the machine and projects some distance beyond the forward end thereof. This bar is provided near its rear end with an abutment 105 (Fig. 120 2) and at its forward end with an operating handle 106. The handle is situated at the pivotal junction of bar 104 with a link 107. This link is fulcrumed on one branch of a forked bracket 108 that extends from the 125 front of the machine, and its end opposite that connected with bar 104 has pivotal connection with one arm of a bell crank 109 that is fulcrumed on the other branch of bracket 108. The bell crank incorporates a 130

belt shifter for coöperation with a belt presently to be introduced. In the vicinity of the abutment 105, the bar 104 is held against upward deflection by a lug 111 that projects from the adjacent side of the cutter carriage.

Projecting from the left hand side of the carriage, near the bottom thereof, are two bosses 113 within which is journaled an adjusting screw 114. This screw is held against lengthwise movement by collars 115 that are secured to the screw adjacent the outside faces of bosses 113. A dog 115, arranged for engagement with lug 105, is threaded on screw 114 and is held against turning by engagement with the side of the cutter carriage. Therefore, as the screw is turned by means of a suitable wrench applied to the squared end of the screw, the dog is moved lengthwise of the carriage.

From the foregoing description it follows that, as the carriage moves forwardly and approaches the end of its course, the dog strikes lug 105 of bar 104, shifting the bar in the same direction, thereby disengaging clutch member 88 from the adjacent gear 85 by reason of the connection of the bar with the clutch through toggle joint 101 and shifting member 97, and shifting the previously mentioned belt from effective position, as I shall presently explain, through the connection of the rod with the bell crank belt shifter 109.

A shaft 116 extends parallel to the left hand side of the machine and at its forward end is journaled in arms 117 and 118 that may be formed integral with bracket 67. The shaft is held against endwise movement by collars 119, located on opposite sides of arm 118. The rear end of the shaft is supported within bearings 120 and 121 that project from the side of bracket 23 which, it will be recalled, is a part of the cutter carriage and consequently moves therewith. A bevel gear 122 is splined to shaft 116 and meshes with a similar gear 123 that is secured to the adjacent end of the saw or cutter arbor 24. To retain these gears in proper relation to each other as the carriage moves with respect to shaft 116, I groove the hub of gear 122 and engage within the groove a rib on a plate 124 that is attached by screw 125 to bearing 121 (see Fig. 2).

Power from any suitable source is introduced through a belt 126 which is shiftable from one to the other of a set of pulleys 126^a and 126^b, the former being loose and the latter fixed on a drive shaft 127. This shaft carries a worm 127^a that is situated between two bearings 128 incorporated in bracket 67 and wherein the drive shaft is journaled. A shaft 129 is supported within the outer ends of the previously mentioned arms 117 and 118. Secured to this shaft is a

worm wheel 130 that meshes with worm 127^a. This shaft also has fastened to it two separate change-speed-gears 131 and 132 with which are adapted to mesh, respectively, the change-speed-gears 133 and 134 70 that are slidably mounted on shaft 116.

Pivoted at 135 to ears projecting from bracket 67 is a member 136 with a forked projection 137 that fits in a groove 138 in a hub that connects the two gears 133 and 134. 75 Said member 136 has secured to it a handle 139 through which it may be operated to shift the gears 133 and 134 thereby to obtain different speeds of the cutter arbor.

Journaled upon shaft 129 adjacent gear 80 131, and confined against movement lengthwise of the shaft by said gear and a collar 140, is the hub of an arm 141. A spindle 142 is journaled within the outer end of the arm and carries a gear 143 on one side of 85 said arm which constantly meshes with gear 131, while on the opposite side of the arm it has secured to it a collar 144, wherefore the spindle is held against longitudinal movement. Slidable and rotatable on shaft 129 90 95 is the hub of a yoke 145 through bearing apertures in the branches whereof extends the spindle 142. A tumbler gear is splined to the spindle between the branches of the yoke and is adapted to be shifted into mesh 95 with any desired member of a cone gear unit 146 through the instrumentality of the yoke as the latter is manipulated by means of its handle 145^a. The yoke may be held in any of its several positions by the engagement of its handle within notches of bracket 94, as indicated in Fig. 5. The cone gear set 146 is secured to the previously mentioned shaft 91.

According to the usual practice, a lubricating oil or cooling solution may be conducted to the various cutters by a system of tubes properly arranged for the purpose, the same being omitted from the drawings for the sake of clearness. When such a system is used, the oil or solution drips off the shelf 53 over the lip 54 into a chip drawer 151 which has holes in its bottom through which the solution drains into a basin 3. A suitable pump would be included in such a 115 system for drawing the oil or solution from the basin and circulating it through the tubes.

The chip drawer 151 may be withdrawn through an opening 151^a in the right hand 120 side of the machine, and the drawer is supported on angle irons 152 extending between and secured to the sides of the machine. The chip drawer is conveniently located under the lip 54 of the table and those chips 125 that are not washed off the table may be readily scraped off into the drawer.

From the foregoing description the operation of the machine will be readily understood. A bar or other piece of work, indi- 130

cated at W, is placed upon the work supports. The handle 70^b is then rotated to turn the spur gears 71 and 72 and feed them along their respective racks thereby to move 5 the main clamping member 62 and the individual clamps 58 rearwardly until they are stopped by the engagement of the lips 59 with the forward ends of work holder projections 56. The shaft 70 is next pulled 10 outward to unclutch the gears from the shaft and clutch the worms thereto. Through the worms the vertical screws 69 are turned and the main clamping member is brought down to bear upon the individual clamps 15 58 and secure the work in place ready to be cut. The handle 106 is pushed to the rear and, through the link connections previously set out, the driving belt is shifted from the loose pulley to the driving pulley 126^b. Simultaneously the clutch member 88 is 20 thrown to effective position; the carriage is fed forwardly, and the cutter arbor 24 starts rotating as will be readily understood. The cutter carriage 10 is stopped in 25 its forward movement after it has cut the stock by the adjustable dog 115 engaging the abutment 105 on the bar 104 and moving the bar forwardly to disengage the clutch 88 and shift the belt to loose pulley 30 126^a. The carriage is then brought back to its initial starting position by the action of weight 22.

Having thus described my invention, what I claim is:—

35 1. In a machine of the character set forth, the combination of means for supporting an article to be cut, a carriage movable toward and from said supporting means, an arbor supported by the carriage at points spaced 40 apart longitudinally of the arbor, a cutter secured to the arbor intermediate of said points, driving mechanism, operative connections between said mechanism and the arbor, and further operative connections between 45 said mechanism and the carriage.

2. In a machine of the character set forth, the combination of a carriage, an arbor supported thereby, a plurality of cutters secured to the arbor, a plurality of holding 50 means for collectively holding an article to be cut and after the article is cut for individually sustaining the pieces cut, driving mechanism, operative connections between said mechanism and the arbor, and further 55 operative connections between said mechanism and the carriage.

3. In a machine of the character set forth, the combination of a supporting structure, a carriage reciprocably supported thereby, 60 means tending to move the carriage to starting position, elements designed for coöperation with each other as means for supporting a piece of work and a tool for operating upon the work, one sustained by the carriage and the other supported in operative 65

relation thereto, mechanism for moving the carriage in a direction to present one of said elements to the other, and means automatically disconnecting the carriage from the mechanism when the carriage has moved 70 a predetermined distance.

4. In a machine of the character set forth, the combination of a supporting structure, a carriage reciprocably supported thereby, means tending to move the carriage to 75 starting position, elements designed for co-operation with each other as means for supporting a piece of work and a tool for operating upon the work, one sustained by the carriage and the other supported in operative 80 relation thereto, carriage advancing mechanism, driving means, a clutch through which the driving means is adapted to be operatively connected to the carriage advancing mechanism, and means for rendering ineffective the aforesaid clutch when the carriage has traveled a predetermined 85 distance.

5. In a machine of the character set forth, the combination of a base, a work support 90 sustained thereby, a carriage movable along the base toward and from the work support, means tending to move the carriage from the support, an arbor sustained by the carriage, a cutter on the arbor, mechanism 95 for driving the arbor and for moving the carriage toward the work support, means actuated automatically when the carriage has moved a predetermined distance for rendering ineffective the connections between 100 the aforesaid mechanism and the arbor and carriage, and manually operated means through which said connections may be re-established.

6. In a machine of the character set forth, 105 the combination of a base, a carriage reciprocable along the base, means tending to move the carriage to starting position, an arbor sustained by the carriage, a cutter secured to the arbor, means for supporting 110 an article to be cut in operative relation to the cutter and toward and from which the carriage is movable, mechanism for rotating the arbor and for moving the carriage in a direction to present the cutter to the 115 article, and means automatically disconnecting the carriage from the mechanism when the carriage has moved a predetermined distance.

7. In a machine of the character set forth, 120 the combination of a base, a work support sustained thereby, a carriage movable along the base toward and from the work support, means tending to move the carriage away from the support, an arbor sustained by the 125 carriage, a cutter on the arbor, mechanism for driving the arbor and for moving the carriage toward the work support, and means actuated automatically when the carriage has moved a predetermined distance 130

for rendering ineffective the connections between the carriage and the aforesaid mechanism.

8. In a machine of the character set forth, the combination of a work support, a carriage movable toward and from the same, means tending to move the carriage away from the support, an arbor sustained by the carriage, a cutter on the arbor, carriage advancing mechanism, driving means common to the arbor and to the carriage advancing mechanism, a clutch through which the driving means is adapted to be operatively connected to the carriage advancing mechanism, a source of power, a member shiftable between effective and ineffective positions and through which the source of power is adapted to be coupled with the driving means, and means for simultaneously shifting the last mentioned member to ineffective position and disengaging the aforesaid clutch.

9. In a machine of the character set forth, the combination of a support, brackets associated with the support, an arbor journaled within said brackets, a plurality of cutters secured to the arbor, a guard associated with each cutter, clamping means common to the guards for clamping them to the support, and means for driving the arbor.

10. In a machine of the character set forth, the combination of a work support, a sustaining structure, means for moving one toward the other of the work support and sustaining structure, an arbor, bearing members for the arbor having parts overlying the sustaining structure, a clamping member disposed above said parts, a plurality of screws through which the clamping member is connected with the sustaining structure, means common to said screws for rotating them in unison to move the clamping members toward and from the sustaining structure, and means for driving the arbor.

11. In a machine of the character set forth, the combination of a support, a plurality of brackets associated with the support, an arbor journaled within said brackets, clamping means common to the brackets for clamping them to the support, and means for driving the arbor.

12. In a machine of the character set forth, the combination of a work support, a sustaining structure, means for moving one toward the other of the work support and sustaining structure, an arbor, cutters secured to the arbor, bearing members for the arbor and guards for the cutters having parts overlying the sustaining structure, a clamping member disposed above said parts, a plurality of screws through which the clamping member is connected with the sustaining structure, means common to said

screws for rotating them in unison to move the clamping member toward and from the sustaining structure, and means for driving the arbor.

13. In a machine of the character set forth, the combination of a work support, a sustaining structure, means for moving one toward the other of the sustaining structure and work support, the sustaining structure having a horizontal surface and a groove traversing the same, a clamping plate, screws through which the clamping plate is operatively connected to the sustaining structure, the clamping plate having a groove substantially parallel to that of the sustaining structure, an arbor, cutters secured to the arbor, arbor supporting means, members embracing the cutters for the purpose specified and having parts disposed between the clamping plate and the horizontal surface of the sustaining structure, said parts being provided with tongues engaged within the grooves of said sustaining structure and clamping plate, means common to the aforesaid screws for rotating them in unison to move the clamping plate toward and from said structure, and driving means for the arbor.

14. In a machine of the character set forth, the combination of a work support, a sustaining structure, means for moving one toward the other of the sustaining structure and work support, the sustaining structure having a horizontal surface and a groove traversing the same, a clamping plate, screws through which the clamping plate is operatively connected to the sustaining structure, the clamping plate having a groove substantially parallel to that of the sustaining structure, an arbor, arbor supporting brackets having parts disposed between the clamping plate, and the horizontal surface of the sustaining structure, said parts being provided with tongues engaged within the grooves of said sustaining structure and clamping plate, means common to the aforesaid screws for rotating them in unison to move the clamping plate toward and from said structure, and driving means for the arbor.

15. In a machine of the character set forth, the combination of a sustaining structure having a clamping surface, a clamping plate, screws through which the clamping plate is supported from the sustaining structure in operative relation to the clamping surface thereof, and means for rotating the aforesaid screws in unison to move the clamping plate toward and from the clamping surface.

16. In a machine of the character set forth, the combination of a sustaining structure having a clamping surface, a clamping plate, screws through which the clamping plate is supported from the sustaining struc-

- ture in operative relation to the clamping surface thereof, either or both the clamping plate and structure having means for coöperation with complementary parts of 5 elements designed to be clamped between the plate and structure thereby to hold the parts in proper position, and means for rotating the aforesaid screws in unison to move the clamping plate toward and from the 10 clamping surface.
17. In a machine of the character set forth, the combination of means for supporting a piece of material to be cut, mechanism for cutting said piece of material into sections, an individual clamp for each section, and mechanism through which the several 15 clamps may be simultaneously operated.
18. In a machine of the character set forth, the combination of means for supporting a piece of material to be cut, mechanism for cutting said piece of material, a clamp for holding the piece of material while being cut, and mechanism through a 20 continuous operation of which the clamp may be moved into operative relation to the piece of material and then into engagement therewith.
19. In a machine of the character set forth, the combination of means for supporting a piece of material to be cut, mechanism for cutting said pieces of material, a clamp for holding said piece while being cut, and mechanism through which the 25 clamp may be released from clamping engagement with the piece of material and then laterally out of operative relation thereto.
20. In a machine of the character set forth, the combination of means for supporting a piece of material to be cut, mechanism for cutting said piece of material into sections, an individual clamp for each section, and mechanism through a continuous 30 operation of which the several clamps may be simultaneously removed from clamping engagement with the sections and then moved laterally out of operative relation thereto.
21. In a machine of the character set forth, the combination of means for supporting a piece of material to be cut, mechanism for cutting said piece of material into sections, an individual clamp for each section, and mechanism through a continuous 35 operation of which the several clamps may be simultaneously moved into operative relation to the piece of material and then into engagement therewith.
22. In a machine of the character set forth, the combination of means for supporting a piece of material to be cut, mechanism for cutting said piece of material into sections, an individual clamp for each section, and mechanism operable in one direction 40 for moving the several clamps simultaneously into operative relation with the sections and then into engagement therewith, and in another direction for releasing the clamps from engagement with the sections and then laterally out of operative relation 45 thereto.
23. In a machine of the character set forth, the combination of means for supporting a piece of material to be cut, mechanism for cutting the piece of material into sections, an individual clamp for each section, a pressure plate arranged to engage the clamps and press them into contact with the sections, operative connections between the plate and clamps whereby lateral movement 50 of the plate is transmitted to the clamps, and mechanism through which the pressure of the plate may be relieved and the plate moved laterally.
24. In a machine of the character set forth, the combination of means for supporting a piece of material to be cut, mechanism for cutting the piece of material into sections, an individual clamp for each section, a pressure plate arranged to engage the 55 clamps and press them into contact with the sections, operative connections between the plate and clamps whereby lateral movement of the plate is transmitted to the clamps, and mechanism through which the pressure of the plate may be regulated and the plate moved laterally.
25. In a machine of the character set forth, the combination of a support for a piece of material to be cut, a clamping member adapted to be brought to bear upon the piece of material or to be removed therefrom and shifted laterally out of operative 60 relation thereto, a screw through which said member is adapted to be moved into and out of clamping engagement with the piece of material, a shaft, gearing through which operative connection may be established between the shaft and screw, a stationary rack, gearing through which operative connection 65 may be established between the shaft and rack, means for rotating the shaft, and means for alternately securing the shaft against rotation with respect to the gearing associated respectively with the screw and rack.
26. In a machine of the character set forth, the combination of means for supporting a piece of material to be cut, mechanism for cutting said piece of material into sections, an adjustable clamp for each section, and mechanism through which the several clamps 70 may be simultaneously operated.
27. In a machine of the character set forth, the combination of a support for a piece of material to be cut, a clamping member adapted to be brought to bear upon the piece of material, or to be removed therefrom and shifted laterally out of operative relation to 75 said piece, a screw through which said mem-

ber is adapted to be moved into and out of clamping engagement with the piece of material, a gear carried by the screw, a shaft, a gear carried by the shaft for coöperation with the former gear, a second gear carried by the shaft, a stationary rack wherewith the last mentioned gear is arranged to coöperate, means for turning the shaft, and further means for locking the shaft against turning with respect to either one or the other of the gears carried thereby.

28. In a machine of the character set forth, the combination of a support for a piece of material to be cut, a clamping member adapted to be brought to bear upon the piece of material or to be removed therefrom and shifted laterally out of operative relation thereto, a screw through which said member is adapted to be removed into and out of clamping engagement with the piece of material, a gear carried by the screw, a shaft, a gear carried by the shaft for coöperation with the former gear, a second gear carried by the shaft, a stationary rack wherewith the last mentioned gear is arranged to coöperate, means for turning the shaft, and further means for locking the shaft against turning with respect to either one of the other gears carried thereby.

30. 29. In a machine of the character set forth, the combination of means for supporting a piece of material to be cut, mechanism for cutting said piece of material into sections, an individual clamp for each section, a member through which the several clamps may be simultaneously engaged or removed from engagement with the material, operative connections between said member and the clamps whereby lateral movement of the member will effect like movement of the clamps, a pair of screws rotatably carried by the member, a slide within which each screw is threaded, a stationary guide for each slide, a stationary rack associated with each guide, a worm wheel on each screw, a shaft supported by the member, means for turning the shaft, worms carried by the shaft, one for coöperation with each worm wheel, gears carried by the shaft, one for coöperation with each rack, and means for locking either the worms or the gears against rotation with respect to the shaft.

30. In combination, an arbor, a pair of collars on the arbor that are held against turning with respect thereto, a cutter on the arbor between the collars, the cutter having an opening, a member projecting from one collar through the opening of the cutter and

into a receiving recess of the other collar whereby the cutter and collars are held against relative turning, and means for holding the collars against movement longitudinally of the arbor.

31. In combination, an arbor, a pair of collars on the arbor that are held against turning with respect thereto, a cutter on the arbor between the collars, the cutter having an aperture and the collars having holes alining with said aperture, a dowel pin extending through the aperture of the cutter and having its ends engaged within the holes of the collars, and means for holding the collars against movement longitudinally of the arbor.

32. In combination, an arbor having a keyway, a pair of collars on the arbor that are provided with keys engaged within the keyway of the arbor, a cutter on the arbor between the collars, the cutter having an aperture, a member projecting from one collar through the aperture of the cutter and into a receiving recess of the other collar whereby the cutter and the collars are held against relative turning, and means for securing the collars against movement longitudinally of the arbor.

33. In combination, an arbor, a pair of collars on the arbor that are held against turning with respect thereto, a cutter on the arbor between the collars, the cutter having a circular series of apertures concentric with its rotating axis, a series of projections on one collar extending through the apertures of the cutter, the other collar having a series of recesses for the reception of the projections of the first collar, and means for holding the collars against movement longitudinally of the arbor.

34. In mechanism of the character set forth, the combination of an arbor, a saw on the arbor, and sets of rollers rotating on a common axis and having comparatively narrow faces engaging the opposite sides of the saw for sustaining the same against lateral deformation, the axes of the sets being radially disposed with respect to the arbor.

35. In mechanism of the character set forth, the combination of a saw, a guard within which the saw operates, and guide rollers carried by the guard and engaging the opposite sides of the saw for sustaining the same against lateral deformation.

In testimony whereof, I hereunto affix my signature.

NATHAN F. FRETTER.
